UNITED STATES PATENT OFFICE.

MYRON B. HAMMOND, OF BRIDGEPORT, CONNECTICUT.

HOSE-SUPPORTER HOOK.

SPECIFICATION forming part of Letters Patent No. 714,300, dated November 25, 1902.

Application filed July 5, 1902. Serial No. 114,473. (No model.)

To all whom it may concern:

Be it known that I, MYRON B. HAMMOND, a citizen of the United States, residing at Bridgeport, in the county of Fairfield and State of Connecticut, have invented certain new and useful Improvements in Hose-Supporter Hooks; and I do hereby declare the following to be a full, clear, and exact description of the invention, such as will enable others skilled in the art to which it appertains to make and use the same.

My invention relates to certain new and useful improvements in hose-supporter hooks by means of which the stocking-engaging members are suspended from the loop element of a corset-clasp.

My present improvement aims to provide a hook which is so constructed that it will be held in position firmly upon the corset-busk without the customary provision of two rearwardly-extending hooks or two hooks for embracing the upper and lower edges of the loop of the corset-clasp.

In the accompanying drawings, which form a part of this application, Figure 1 is a front elevation showing my improved device in position on a corset-busk; Fig. 2, a rear elevation of the same; Fig. 3, a perspective view of my improved hook, and Figs. 4 and 5 are respectively front and rear elevations of a modified form of my improvement in position on a corset-busk.

Similar numbers of reference denote like parts in the several figures of the drawings. 35 1 represents a corset-busk having the loop 2 of a corset-clasp secured thereto in the usual manner.

3 is a sheet-metal plate having at the upper end a lateral extension 4, which projects from 40 the front edge of the plate and is formed into a hook 5, which is parallel with the extension itself.

6 is a hook which extends rearwardly from the front edge of the plate and is parallel 45 with the latter. The distance between these hooks is slightly greater than the width of the loop, so that the device may be placed in position for use with the hook 5 engaging the upper edge of the loop, while the hook 6 is 50 immediately beneath the lower edge of the loop. As shown in the drawings, the plate is in front of the busk, while the hook 6 is in the rear of the same and snugly embraces it, so that the plate is thereby firmly held in position.

The stocking-engaging members form no part of my present improvement, and they may be secured to the bottom of the plate in any suitable and well-known manner, and in the present instance I have shown an ordinary 60 slot 7 in the bottom of the plate through which these members may be secured.

In the modification shown at Figs. 4 and 5 the hook 5 engages the lower edge of the loop 2, while the hook 6 engages with the corset-busk 65 immediately above the upper edge of said loop, and thereby supports the device, and this construction is substantially like that shown in Figs. 1 and 2, except that in these last two figures the hook 5 engages with the 70 upper edge of the corset-loop, and thereby supports the device, while the hook 6 engages the corset-busk immediately below said loop. The plate 3 is cut away near the top merely for the purpose of affording a little more 75 resiliency to the plate.

Having thus described my invention, what I claim as new, and desire to secure by Letters Patent, is—

1. A hose-supporter hook comprising a plate 80 which has an extension projecting forwardly from its front edge and a hook formed integral with one side of said extension and parallel therewith, said plate also having a second hook which extends from its front edge 85 rearwardly parallel with said plate, said hooks extending in directions at right angles to each other and separated by a space which is sufficient to permit the insertion of the loop of the corset-clasp between said hooks, substan- 90 tially as set forth.

2. In a hose-supporter hook, a plate capable of being attached to stocking-engaging members, the upper part of the side edge of said plate having a forwardly-extending hook 95 element which opens downwardly and is adapted to engage with and rest upon the upper edge of the loop of the corset-clasp, said plate also provided with an elongated hook at a distance from the first-mentioned 100 hook and extending rearwardly and parallel with said plate and opening laterally, substan- tially as set forth.

In testimony whereof I affix my signature in presence of two witnesses.

MYRON B. HAMMOND.
